CATHODE RAY TUBES

Ralph Reginald Pearce, Hampton, England, assignor to Electric & Musical Industries Limited, Hayes, Middlesex, England, a company of Great Britain

Application January 27, 1956, Serial No. 561,827

Claims priority, application Great Britain
February 12, 1955

12 Claims. (Cl. 313—70)

The present invention relates to cathode ray tubes having a plurality of electron gun structures.

Cathode ray tubes having a plurality of gun structures so as to produce a plurality of electron beams have been proposed for various purposes, one important application for such tubes being for the reception of television pictures in colour. The various individual guns are each modulated with information signals concerning a particular colour and the guns are grouped so that the individual beams are directed on to a common luminescent target having an array or pattern of phosphor particles disposed thereon which on being struck by electrons produce different coloured light i.e. red, green and blue.

The manner of grouping the electron guns will depend to a large extent on the phosphor pattern on the target and at present two such arrangements are well known. In one arrangement three guns are provided in the neck of the tube and positioned symmetrically around the neck axis and each slightly inclined thereto, so that the three electron beams arriving at the target or at a shadow mask provided adjacent thereto, form the apices of small equilateral triangles. In a second arrangement, the three electron guns are mounted side by side in one plane, the centre gun having its axis coinciding with the axis of the neck of the tube and the outer guns each being inclined towards the tube axis so that three focussed spots are formed at or near the phosphor target, in line and at a small distance apart.

With such arrangements the practice is to construct each of the guns with independent electrostatic focussing means for each of the beams in order to overcome the difficulties, which would arise with a common magnetic or electrostatic focussing means for such widely separated and inclined beams. The diameter of the neck of the tube, the angle of convergence of the beam and the overall length of the tube will impose limitations on the diameters of the lenses which can be employed for the three guns, particularly in the simple side by side arrangement, which results in an unfavourable ratio of lens to beam diameter and consequent aberration in the focus, especially in the highlights of the picture. The beam diameter is usually set by electron optical considerations in the gun design and it is desirable to increase the diameters of the lens electrode as much as possible.

It is therefore an object of the present invention to provide an improved arrangement for providing a plurality of electron gun structures in a cathode ray tube whereby the lens to beam ratio of the individual guns can be improved.

Accordingly the invention comprises a cathode ray tube having a plurality of independent guns arranged as a group within the tubular neck portion of the envelope of said tube, wherein one of said guns is displaced so as to occupy a different axial position along the length of said neck than another or other guns of said group whereby

2

the beams emerging from said guns can be positioned closer to each other than would otherwise be possible with similar guns all arranged at the same axial position in said neck.

In order that the invention may be clearly understood and readily carried into effect, embodiments of same will now be more fully described with reference to figures of the accompanying drawings, in which:

Figure 1 shows one arrangement for a group of three guns housed in the neck portion of a cathode ray tube envelope, said guns facing a luminescent target electrode,

Figure 2 shows an alternative arrangement of guns having modified gun electrodes, and

Figure 3 illustrates a gun arrangement similar to that of Figure 1 but with a modified gun structure.

Referring to Figure 1 there is shown three electron guns each comprising a thermionic cathode 1, an apertured grid electrode 2, an apertured disc anode electrode 3 having attached thereto an annular extension 4, a second anode electrode 5 of tubular form and a third anode electrode 6 also of tubular form. In operation of the tube the signal potentials are applied to each gun between the cathode 1 and modulating electrode 2 and the anode 3 maintained at a suitable potential with respect to the cathode 1. A positive potential with respect to the cathode 1 is applied to the second anode 5 and a much higher positive potential to the third anode 6 so that an electrostatic lens is formed between these electrodes to focus the electron beam to a spot on to a target electrode such as a fluorescent screen disposed on the inner surface of the end wall 7 of the tube envelope. In the particular example shown the fluorescent screen comprises a series of strips of different phosphors 8, 9, 10 which on bombardment by electrons fluoresce in different colours i.e. red, green and blue, said strips as shown being arranged to extend across the end wall 7 in a direction normal to the plane of the drawing. It will be observed that the anodes 5 and 6 each have a larger diameter at the position 11 where the electron lens is formed and it is this diameter, termed lens diameter, which determines the closeness with which the electron guns can be disposed as a group in the glass neck 12 of the cathode ray tube. A wall anode 13 is provided extending between the ends of said guns and the target.

For electron optical reasons the lens diameter should be as large as practical and further it is desirable, particularly with cathode ray tubes employed for colour television that the focussed beam spots should form an accurate closely spaced group at the position of the target.

In the example illustrated the three electron guns are shown disposed in a single plane with the axis of the centre gun coincident with the axis of the cylinder 12. However the centre gun is arranged at a different axial position along the neck 12 compared with the outer guns of the group. In order to provide a suitable convergence of the beams of the outer guns on to the target these guns are arranged with their respective axes inclined towards the axis of the neck 12, and to prevent interaction between the beams due to the positioning of the centre gun, the anodes 6 of the outer guns are each provided with a tubular extension 14 so that the beam exit apertures of all three guns are at approximately the same axial position. The provision of the annular extensions 4 on the anode 3 will serve to screen the modulator 2 and anode 5 from any disturbing field conditions which may be set up due to the proximity of high potential electrodes of adjacent guns, particularly, the centre gun in respect to the fields of the anodes 6 of the other two guns. To further minimise any possibility of distortion of the lens fields due to the proximity of the other guns, the space 11

between the anode electrodes 5 and 6 may be screened in any suitable manner such as illustrated in Figures 2 and 3. In these figures parts similar to those of Figure 1 are given the same reference numerals. Referring to Figure 2 it will be seen that the larger end of each of the anodes 6 is of slightly smaller diameter than the diameter of the adjacent portions of the anodes 5 so that the ends of the anodes 6 project for a short distance into the anodes 5 thereby screening the lens space between these electrodes from the fields of adjacent guns.

A slightly different arrangement for screening the lens spaces of the guns is shown in Figure 3 and comprises annular screen members 15 surrounding the lens gap between anodes 5 and 6 for each gun. These members 15 may be connected electrically either to anode 5 or to anode 6.

The amount by which the centre gun can be displaced with respect to the other guns will depend in the above arrangements on the angle of convergence required in the beams, the separation of the gun axes at a given distance from the target, the lens diameters, the diameter, and total length of the neck.

A further advantage which arises from the use of a series of guns grouped according to the invention is that individual corrections of the angle of convergence of the outer guns in a side by side arrangement or of all guns in a symmetrical arrangement, by magnetic means to take account of inaccuracies in assembly is simplified, in that magnetic fields local to any particular gun can be set up so as to have little or no effect on the beams from the other guns.

Various modifications may be made in the manner of staggering the various guns of the group, for example, as shown in Figure 2, the outer guns of the arrangement above described may be set forward of the centre gun, and it will of course be understood that guns having a different electrode arrangement such as those illustrated in Figures 1 and 3 may also be employed and positioned in the manner shown in Figure 2.

It will be appreciated that since each of the guns is in operation, independent of the other guns, adjustments to effect a change in the focal length of the lenses to compensate for their different positions in the tube may be effected electrically by slightly changing the voltage ratio applied to the anodes 5 and 6, or if preferred the length and/or diameter dimensions of the anodes 5 of the two outer guns may be made different from the dimensions of anode 5 of the centre gun.

Although the invention has been described applied to cathode ray receiving tubes it is also applicable to transmitting tubes and generally to cathode ray tubes irrespective of purpose where a plurality of guns are required with their respective beams focussed into a group of spaced spots on to a suitable target electrode.

What I claim is:

1. A cathode ray tube having an envelope including a tubular neck, a target within said envelope facing said neck and a plurality of electron guns within said neck facing said target, said guns each having means for producing an independent electron beam and electrodes providing an electrostatic lens for focussing its electron beam at said target so that the focused beams of said plurality of guns arrive at said target as a group of spots which are spaced from each other, the electrodes forming the electrostatic lens of each of said guns being of substantially the same cross-sectional dimensions for each gun at said lens position, one of said guns being provided with an electrode portion which is of a smaller cross-sectional dimension than the electrodes at said lens position and another of said guns arranged with its electrode at its lens position disposed adjacent the electrode of smaller cross-sectional dimension of said first mentioned gun with said electrostatic lenses of said first and second guns displaced so as to occupy different axial positions along the length of said neck and such that said guns are positioned

closer to each other than would otherwise be possible with a similar plurality of guns having electrodes providing the same lens diameter arranged with said electrostatic lenses at the same axial position in said neck.

5 2. A cathode ray tube according to claim 1 in which one of said guns is provided with electrodes spaced apart and forming therebetween the electrostatic lens of said gun wherein means is provided surrounding the position at which said lens field is formed between said spaced electrodes to substantially shield said lens from the field of an electrode of an adjacent gun.

10 3. A cathode ray tube according to claim 1 in which one of said guns includes two spaced tubular electrodes forming the electrostatic lens of said gun, wherein an electrically conducting member is provided surrounding the space between said tubular electrodes said member being electrically connected to one of said tubular electrodes to substantially shield said lens from the field of an electrode of an adjacent gun.

15 4. A cathode ray tube according to claim 1 wherein the electrostatic lens of one of said guns is produced by a pair of tubular electrodes of different cross sectional dimensions, the electrode of smaller cross section projecting into the electrode of larger cross section to an extent such as to substantially shield the electrostatic lens field formed between said electrodes from the field of an electrode of an adjacent gun.

20 5. A cathode ray tube according to claim 1 wherein the beam exit apertures of each of said guns is arranged at substantially the same axial position along the neck of said tube.

30 6. A cathode ray tube according to claim 1 wherein one of said plurality of guns is arranged with its axis substantially coincident with the axis of said tubular neck and another of said guns is arranged with its axis tilted toward the axis of said first mentioned gun.

35 7. A cathode ray tube according to claim 1 wherein a group of three electron guns are provided, and said target comprises a luminescent screen providing three different colours the means for producing said different colours being arranged in a pattern of triplet groups over said target, the electron beams from said electron guns having such an angle of convergence that the beam from each of said guns will impinge on a different colour producing means on arriving at a triplet group at said target.

40 8. A cathode ray tube having an envelope including a tubular neck, a target within said envelope facing said neck and a group of three electron guns within said neck facing said target said guns each having means for producing an independent electron beam and electrodes of substantially the same cross-sectional dimensions for forming an electrostatic lens for focusing said beam at said target, said electron guns being mounted side by side in a common plane with the axes of the two outer guns converging in the direction towards said target one of

45 said guns being provided with an electrode portion which is of a smaller cross-sectional dimension than the electrodes at said lens position and one of said guns being displaced so as to occupy a different axial position along the length of said neck with the electrode at its lens position disposed adjacent the electrode of smaller dimension of said other gun such that said three guns can be positioned closer to each other for a prescribed angle of convergence of said beams than would otherwise be possible with three similar guns mounted in a common plane and all arranged at the same axial position in said neck.

50 9. A cathode ray tube according to claim 8 wherein the axis of the center gun substantially coincides with the axis of said neck with said outer two guns having their axes tilted towards the axis of said center gun the electrostatic lens of said center gun occupying a different axial position along the length of the neck of said tube than the electrostatic lens of said outer guns.

55 10. A cathode ray tube according to claim 8 wherein said target comprises a luminescent screen composed of

a repeating sequence of groups of line phosphors each group providing three different colours, said guns being arranged such that the angle of convergence of said beams is such that each individual beam strikes a different colour phosphor of a group.

11. A cathode ray tube according to claim 8 wherein the center gun of said three guns is of greater axial length than the outer two guns said center gun being disposed with its axis substantially coincident with the axis of the tubular neck with said outer two guns disposed with their axes tilted towards the axis of said center gun, the exit aperture of each of said guns being arranged at substantially the same axial position along the neck of said tube.

12. A cathode ray tube according to claim 8 wherein the outer guns of said three guns are of greater axial length than the center gun, said center gun being disposed with its axis substantially coincident with the axis of the

tubular neck with said outer two guns disposed with their axes tilted towards the axis of said center gun, the exit aperture of each of said guns being arranged at substantially the same axial position along the neck of said tube.
